ATTORNEY

UNITED STATES PATENT OFFICE.

CHARLES C. KELTY, OF POAST TOWN, OHIO, ASSIGNOR OF ONE-FOURTH TO MORRIS W. RENICK, OF MIDDLETOWN, OHIO.

RAIL CLAMP.

Application filed July 21, 1926. Serial No. 124,039.

My present invention has reference to railway track constructions.

My object is to provide a concrete bed that has embedded therein the headed ends of bolts, the said bolts passing through metal plates upon which the rails rest, and likewise engaging with means for effectively clamping the rails on the plates so that the rails will be held against movement in any direction except a limited longitudinal movement incident to expansion and contraction and further whereby the portions of the rails between the plates will be afforded the desired and necessary resiliency.

15 A still further object is the provision of a rail bed, supporting means for rails, and means for effectively clamping the rails on the supporting means, the same clamping and securing means being employed at the 20 joints between the rails as well as at the body of the rails.

To the attainment of the above broadly stated objects and many others which will present themselves as the nature of the invention is better understood, the improvement resides in certain other novel features of construction, combination and operative association of parts, a satisfactory embodiment of which is disclosed by the accompanying drawings.

In the drawings:

Figure 1 is a top plan view showing a rail clamped on a bed in accordance with this invention, a part of the rail being in section.

35 Figure 2 is a section on the line 2—2 of Figure 1.

Figure 3 is a top plan view of one of the clamping plates.

40 Figure 4 is a sectional view similar to Figure 2 but showing the arrangement of parts when fish plates connect the meeting ends of two rails.

Figure 5 is a plan view of one of the rail plates.

45 Figure 6 is a detail sectional view approximately on the line 6—6 of Figure 2.

Figure 7 is a similar sectional view approximately on the line 7—7 of Figure 4.

50 Figure 8 is a bottom plan view of one of the washers employed.

Figure 9 is a detail sectional view on the line 9—9 of Figure 1.

The road bed 1 is of concrete. Anchored in the bed 1 there are the headed ends 2 of

bolts 3. The bolts are arranged in spaced pairs and the threaded shanks thereof project vertically through the bed 1. In instances where the bolts are to be arranged in an old bed or to be inserted in a concrete bed when the improvement is employed in connection with street railways, the bolts instead of being headed are of the expansible type, but in each event the shanks of the bolts project through the top of the bed.

Arranged on the top of the bed at determined spaced intervals there are rail plates 4. The plates 4, adjacent to their ends, and close to their diagonally opposite corners are provided with openings 5 through which the respective pairs of bolts 3 pass. The 70 plates 3 are formed on the upper faces thereof with transversely arranged flanges 6. These flanges are cut-away for a suitable distance from the sides of the respective pairs of openings 5. The flanges 6 are designed 75 for contacting engagement with the base flanges of rails 7 which rest on the plates 4.

The rail clamps are indicated by the numerals 8 and are all of a similar construction. Each rail clamp includes a flat body portion 80 that is provided with a pair of spaced elongated openings 9 and with an upstanding angle portion that provides a rail engaging lip 10'. The shanks of the bolts 3 are designed 85 to be passed through the openings 9. Of course, the shanks 3 of the bolts are round in cross section and in order to fill the space between the bolts and one of the rounded end walls provided by each of the openings 9, I 90 provide depending lugs 10 on washer members 11. The washer members are disposed over the clamping plates and are engaged by the nuts 12 that are screwed on the bolts 3.

The lugs 10 have their inner ends in a line with the central round opening through the 95 bolts and therefore these ends are concaved, as at 13, while the outer ends of the lugs are rounded, as at 14 for snug engagement with the rounded end walls provided by the openings 9.

When plates 15 connect the confronting ends of two of the rails 7, the clamping plates are arranged as disclosed by Figure 4 of the drawings, that is, the pairs of bolts 3 are disposed to contact with the rounded walls provided by the openings 9 nearest the lip 10' of the clamp 8 and the washers are 105 reversely arranged so that the lugs 10 will con-

tact with the outer surfaces of the bolts, and with the outer rounded walls provided by the said openings 9.

The simplicity and advantages of my construction will, it is thought, be perfectly apparent to those skilled in the art to which such invention relates when the foregoing description is read in connection with the accompanying drawings. It will be apparent that with my improvement the rails are effectively clamped on the bed, the said rails at the portions thereof between the rail plates are afforded the necessary resiliency and the bolts may be anchored in new road beds or in concrete road beds which have been already constructed. Because of the vast use of lumber, wooden ties are expensive and are hard to procure, and it will be noted that my improvement dispenses with the employment of such ties.

Having described the invention, I claim:—

1. A concrete road bed having bolts arranged in spaced pairs anchored therein and extending therefrom, rail plates through which the bolts pass and said plates designed to have rails received thereon, upstanding spaced flanges on each rail plate contacting with the outer edge of the base flanges of the rails, rail clamping plates having lip ends and having their bodies provided with elongated openings through which the bolts pass, washer members arranged on the bolts and

having depending lugs received in the openings of the clamping plates for contacting with the bolts and with one of the end walls 35 provided by said openings and nuts screwed on the bolts.

2. A concrete road bed, bolts arranged in spaced pairs anchored therein and projecting therefrom, metal rail plates through which the bolts pass and on which rails are designed to rest, each of said plates having laterally extending spaced pairs of flanges designed to contact with the base flanges of the rails, rail clamping plates having lipped ends 45 and having their bodies provided with longitudinal elongated openings whose end walls are rounded and through which the bolts pass, a washer arranged on each bolt, said washer having a depending lug whose inner 50 wall is arranged in a line with the central opening in the washer and concaved and whose outer wall is rounded, said lugs adapted to be received in the mentioned openings 55 so that the rounded ends thereof will contact with one of the end walls of the said opening and the concaved end thereof will contact with either side of the bolt and whereby the clamping plates may have their lipped ends brought into contact with the webs of the rails or away from such contact and nuts screwed on the bolts.

In testimony whereof I affix my signature.

CHARLES C. KELTY.
